UNITED STATES PATENT OFFICE

166,441

BARBECUE FORK

Malcolm C. Bert, Jr., Inglewood, Calif.

Application July 8, 1950, Serial No. 11,007

Term of patent 7 years

(Cl. D44—29)

To all whom it may concern:

Be it known that I, Malcolm C. Bert, Jr., a citizen of the United States and a resident of Inglewood, in the county of Los Angeles and State of California, have invented a new, original, and ornamental Design for a Barbecue Fork, of which the following is a specification, reference being had to the accompanying drawing, forming a part thereof.

The dominant features of my new design have been shown in solid lines.

I claim:

The ornamental design for a barbecue fork, substantially as shown and described.

MALCOLM C. BERT, JR.
